ADJUSTABLE YARN TENSION DEVICE

Ralph H. Carter and Richard Gollong, Johnson City, and Chadwick B. Kingsbury, Elizabethton, Tenn., assignors to North American Rayon Corporation, New York, N. Y., a corporation of Delaware

Application July 29, 1939, Serial No. 287,288

11 Claims.

(Cl. 57—58)

This invention relates to an adjustable yarn tensioning device and more particularly to a mechanism for use in conjunction with a spinning or twisting device of the kind adapted to impart two twists to the yarn, thread or the like for each revolution of the spindle.

The specific improvement contemplated by this invention is the provision of a simple rugged mechanism for insuring that the yarn will be subjected to a predetermined uniform tension during the twisting operation in order to control the rate of speed with which the yarn is drawn from the bobbin and thus eliminate irregular twisting of and defects in the yarn and produce a finished yarn of uniform twisting properties.

The device herewith disclosed may be used with apparatus in which the yarn package from which the thread is drawn does not partake in the revolution of the twisting device. In such devices, the thread is drawn off from a stationary package and led downwardly through a hollow rotating spindle, then outwardly around the yarn package where it forms a balloon owing to the high rotational speed of the spindle, and finally to a takeup device. The size of the balloon formed by the thread during twisting depends upon the rotational speed of the spindle and particularly upon the rate of speed with which the yarn is drawn from the package. It is obvious that a balloon formed by a heavy thread will draw the thread from the source of supply at a much faster rate of speed than a comparatively light thread, which is due to the high centrifugal force set up in the thread during ballooning. In the artificial silk industry, for example, where threads ranging from about 50 to 600, 800 or more denier are produced, the high denier thread will draw the thread much faster from the yarn package than a comparatively light thread of, for example, 50 denier, owing to the much greater centrifugal force during ballooning of the high denier thread. If, however, an adjustable braking means is inserted in the path of the thread from the spool to the ballooning area, the pull of the balloon on the thread drawn from the package may be regulated.

It is therefore one object of the present invention to provide a cap for twisting spools wherein the thread to be twisted is fed from the stationary yarn package in a downward axial direction of the package through a hollow rotating spindle, while subjecting the yarn to the influence of an adjustable brake or tension

mechanism which will insure, that the yarn will receive a precise tensioning action.

Another object is to construct such an adjustable yarn tensioning mechanism that may be readily assembled and disassembled and which will give the operator precise control over the amount of tension imparted to the yarn.

A further object is to construct the braking arms of the device so that they may be easily released from contact with the yarn for adjustment and the like and to fabricate the braking or tensioning members per se of a material which will not be scored or indented by the yarn passing therebetween.

15 Another still further object is to provide means for releasing the tensioning members and thus permit easy threading of the spindle and the ready removal of broken thread, slubs and the like.

20 In the drawings,

Fig. 1 is a vertical sectional view showing the yarn package on the spindle and the balloon formed by the twisted yarn;

Fig. 2 is a side plan view of the twisting cap 25 per se;

Fig. 3 is a bottom plan view of the twisting cap;

Fig. 4 is a separating key;

Fig. 5 is an enlarged vertical cross sectional view of the twisting head and tension device;

Fig. 6 is a top plan view taken on line 6—6 of Fig. 9;

Fig. 7 is an enlarged detail partly in cross section of a modified form of tension arm;

Fig. 8 is a bottom plan view taken on line 8—8 of Fig. 9; and

Fig. 9 is a vertical section of the twisting head partly in cross section.

The package of yarn 1 to be twisted is carried 40 on a spool or bobbin 2 fitted on base 3 affixed to disc 4 which is mounted on cup 5. The conventional rotating mechanism indicated collectively by numeral 6 is arranged to turn the hollow spindle 10 and it will be understood that this mechanism may be of any desired type as is well known in the art.

The hollow rotating spindle 10 has a vertical bore 11 and side opening 12 therein for the passage of the thread, as will be hereinafter described. A stationary tube-like member 13 surrounds the operative tip 14 encompassing the upper end of the spindle 10 and extends upwardly to form a support for the twisting cap and adjustable tension device broadly designated 15.

Specifically, the cap 15 comprises an annular support 20 fitted over the end of tube 13 and surrounding the yarn centering ferrule 21. The enlarged diameter portion 25 of the cap is screwed or otherwise secured to the base plate 24 of the cone shaped casing 26 which terminates in twisting head 27 having a ring-like shoulder 28 and central tapered bore 29. The cone casing 26 is hollow and has a pair of opposite cut-away sections 30 and 31.

A pair of spaced pivot blocks 35 and 36 are integrally formed with the base plate 24 and provided with pivot pins 37 and 38, respectively, upon which are mounted angled bracket arms 39 and 40. Each bracket arm, as shown in detail in Figs. 5 and 6, is provided with an upper offset socket 41 having an aligned bore 42 and restricted opening 43 for the retention of spring 44 and rounded catch pin 45 which normally engages an arcuate socket 46 formed on the under-sides of head 27 at the cut-away sections 30 and 31, see Fig. 3.

The angled bracket arms 39 and 40 have mounted on their meeting faces friction pads or brakes 50 and 51, retained in sheet metal holders 52 and 53, respectively, which clamp the friction members and extend rearwardly to embrace the back of the arms 39 and 40 (see Fig. 6), the vertical position of the pad being maintained by horizontal stop pins 54. It is preferable to have at least one of the holders 52 and 53 adjustable with relation to its arm and opposite pad and to this end the holder arms are extended rearwardly so as not to bind against the back of its arm 39. To create a constant pressure on the friction pad 51, a spring pressed plunger 55 encased in a screw threaded tube 55' is threaded through the bracket arm 39 with a screw threaded cap 56 bearing on the rear end of coil spring 57. Consequently when the cap 56 is turned, the pressure exerted by the pad 51 against the opposite pad may be adjusted.

As before described, the upper ends of the bracket arms and pads are normally in contact with each other and are retained in this position by engagement of the pins 45 with the arcuate grooves 46. This is also assisted by springs 58 and 59 encircling the pivots 37 and 38, respectively.

When it is desired to separate the pads 50 and 51 for replacement, adjustment, rethreading and the like, a key 80 having a blade 81 is inserted through a bore 82 formed at right angles to the bracket arms 39 and 40. The blade 81 is placed between the arms below the pads and given a quarter turn which is sufficient to snap the spring pressed pins 45 out of engagement with their locking grooves 46. After rethreading or adjustment has been made, the bracket arms may be readily locked into engagement again by applying pressure to the arms through openings 30 and 31.

In Fig. 7 there is illustrated a modified form of the arm and friction pad holder wherein the pivoted arm 39' has a pad 51' and holder 53' with constant tension devices 42' and 55'. These devices comprise hollow sheet metal casings having openings 60 and 61 in the bottom surfaces thereof through which projects rounded buttons 62-63 whose enlarged bases 64-65 are pressed by coil springs 66-67. Plates 68-69 are fitted inside the casings and the enlarged ends of the casings are crimped to retain the plates in place.

In the modified form of the tension device disclosed in Figs. 8 and 9 of the drawings, the 75

pivoted arms 39' and 40' and associated mechanism are similar to the preferred form, the difference being the construction of the head 27. Here, instead of having a key 80 and opening 82 for separating the brake arms, the spring catches 62 are retained within interrupted arcuate grooves 70. Oppositely positioned screws 71 and 71' pass through the upper part of the cone and terminate within interrupted slots 72-72'. Thus, when the head 27 is rotated through a 90° angle, it positions the upper ends of the arms 39' and 40' opposite interrupted portions of the head having no arcuate ridge or grooves and the arms will pivot outwardly through sections 30' and 31'.

In operation, the yarn from the package 1, as shown in dotted lines, is led from the spool or bobbin 2 downwardly through cap opening 29 between opposed tension pads 50-51, guide 21, hollow rotating spindle 11 and outwardly from the bottom opening 12, and thence balloons around the mechanism to a suitable collection device. During its path from the point of unwinding from the yarn package to the point of collecting, the yarn or thread receives a double twist since the yarn package is stationary while the spindle through which the yarn is led rotates at a high rate of speed. The tensioning device inserted in the path of thread between the point of unwinding and the ballooning area, because of its adjustability, makes it possible to apply uniform tension on the thread and thus regulate the rate of take-off of thread from the yarn package.

The use of a tensioning device having outwardly pivoted arms as described permits the twister to be readily threaded and rethreaded if breakage occurs, and ready access for removing slubs, broken threads and the like. As before stated, however, the principal advantage of the present invention is the resultant uniform tension placed on the yarn.

Experiments made with various materials for use in the braking or friction pads 50 and 51 have shown that a combination of sponge rubber pads faced with a thin woven glass fabric has given very satisfactory results. In this combination, although the resiliency of the material is not impaired, the pads maintain a uniform flat surface and contact against the yarn passing therebetween. By having one pad adjustable with relation to the other, as previously described, the tension between the abutting surfaces may be regulated with facility and a constant pressure between the pads continuously maintained. The adoption of glass fabric and rubber pads eliminates the scoring and indenting of the material by the thread as is usually experienced with ordinary resilient material, and the use of these novel brake surfaces in conjunction with adjustable spring pressure means has proven most satisfactory. If desired the brackets may also be equipped with a washboard tension device similar to those used on coning machines, in place of the aforementioned resilient pads.

It is to be understood that the form of our invention, herewith shown and described, is to be taken as a preferred example of the same, and that various changes in the shape, size and arrangement of parts may be resorted to without departing from the spirit of our invention or the scope of the subjoined claims.

Having thus described our invention as required by the patent statutes, what we claim is:

1. A yarn twisting mechanism of the character

described comprising a rotating drive spindle, a non-rotating bobbin removably mounted on the free end of said spindle, and having a yarn package wound thereon, said spindle and bobbin having a central yarn passage therethrough, and a tension device carried on the upper end of said bobbin, said device having a pair of pivoted arms having opposed and abutting friction surfaces thereon between which the yarn from said package is drawn to create a uniform tension therein.

2. A yarn twisting mechanism as set forth in claim 1, wherein the opposed friction surfaces are formed of pads consisting of non-scoring resilient material.

3. A yarn twisting mechanism as set forth in claim 1, wherein the opposed friction surfaces are formed of resilient pads having glass cloth faces.

4. A yarn twisting mechanism as set forth in claim 1, wherein the tension device comprises a pair of upstanding pivoted arms between which the yarn from said package is drawn by the rotating spindle, and latch means carried on the upper ends of the arms for normally holding said arms in contact with each other.

5. A yarn twisting mechanism as set forth in claim 1, wherein the friction surfaces between which yarn is drawn are mounted on the opposing abutting faces of a pair of pivoted arms, with positive means for separating said arms.

6. A yarn twisting mechanism as set forth in claim 1, wherein the friction surfaces between which the yarn is drawn are mounted on pivoted arms, and resilient means affixed to one of said arms for varying the degree of contact of one of the surfaces with the other of said surfaces.

7. A yarn twisting mechanism of the character described comprising a rotating drive spindle and a non-rotating yarn package mounted on the free end of said spindle, said spindle and yarn package having a central yarn passage therethrough, a hollow conical member removably mounted on the free end of said yarn package, said conical member having a pair of pivoted contacting arms secured therein between which the yarn from said package is drawn to create a uniform tension therein.

8. A twisting apparatus of the type described including a fixed hollow yarn package and a hollow rotating spindle mounted within the yarn package, a braking device interposed between the said yarn package and the said rotating spindle, said braking device being mounted on the upper end of said yarn package and comprising a centrally apertured hollow cone member, a pair of pivoted upstanding arms having abutting flat friction faces secured within said cone, the central aperture in said cone together with the inner surfaces of said friction faces being in vertical alignment with said rotating spindle.

9. A twisting apparatus of the type described including a hollow rotating drive spindle and a non-rotating yarn bobbin removably mounted over an upstanding tube member surrounding said spindle, a removable yarn tensioning device supported on the free end of said bobbin and said tube member, said device comprising a substantially hollow cone member, a pair of opposed abutting arms pivoted therein, the upper ends thereof being latched within said cone, a yarn aperture in the apex of said cone above the said pivoted arms, opposite cutaway portions in the surface of said cone, a horizontal bore in the surface of said cone midway between said cutaway portions, and a key adapted to be inserted in said bore and wedged between the lower portions of said arms, said key upon rotation unlatching said arms and permitting them to pivot outwardly into the said cutaway portions.

10. A twisting apparatus of the type described including a hollow rotating spindle, a stationary tube surrounding said spindle, a yarn package removably mounted over said spindle and tube, a removable yarn tension imparting device mounted on the upper ends of said yarn package and said tube, said device comprising a hollow cone having an oscillatable apex portion, a pair of pivoted arms secured within said cone, abutting braking faces carried on the said arms, each arm having an upwardly extending spring projected latch member secured within the upper end thereof, cutaway portions in said cone adjacent the rear of each of said arms, and a pair of interrupted arcuate grooves formed on the underside of the oscillatable apex portion of said cone for normally retaining the said latch members and for releasing the same when the said apex portion is rotated through a one-quarter turn.

11. A twisting apparatus of the type described including a hollow rotating spindle, a stationary tube surrounding said spindle and a non-rotating yarn bobbin removably mounted over said spindle and tube, a removable yarn tensioning device fitted over the end of said bobbin and said tube, a pair of pivoted arms carrying abutting glass cloth surfaces secured within said tension device, means for adjusting the degree of contact between said glass cloth surfaces and for separating the said surfaces, the yarn to be twisted being fed upwardly from said bobbin and drawn downwardly through said tension device between said glass cloth surfaces and through said hollow spindle by the rotating action thereof to create a uniform tension in said yarn.
